(57) CLAIM

The ornamental design for a nameplate, as shown and described.

DESCRIPTION

FIG. 1 is a front perspective view of a nameplate showing our new design;

FIG. 2 is a front elevational view thereof;

FIG. 3 is a left side elevational view thereof;

FIG. 4 is a right side elevational view thereof;

FIG. 5 is a bottom plan view thereof; and,

FIG. 6 is a top plan view thereof.

It is to be noted that the broken lines indicating "NEXT TELLER PLEASE" shown in FIGS. 1 and 2 represent unclaimed environmental structure only and form no part of the claimed design.
